DISTILLING PRESSURE CONVERTED PRODUCTS BY CONTAINED HEAT

Edward J. Shaeffer, George W. Watts, and Eugene P. Brown, Whiting, Ind., and Robert E. Wilson, Chicago, Ill., assignors to Standard Oil Company, Whiting, Ind., a corporation of Indiana

Application April 10, 1926. Serial No. 101,103

20 Claims. (Cl. 196—73)

The present invention relates to improvements in the handling of pressure-conversion oil products such as the tar or residuum from pressure stills or converters in which pyrolytic conversion of hydrocarbon oils into gasoline and like products takes place. It is more particularly intended for use in connection with systems in which there is a continuous withdrawal of heated tar or residuum from the pressure system. It may also be employed in connection with a system in which there are a plurality of units in which pressure distillation takes place, the withdrawal of tar or residuum from any one of such units being intermittent, but so timed with respect to the others as to give a roughly continuous supply of heated pressure tar to be operated upon. It will be fully understood from the following description illustrated by the accompanying drawing, in which apparatus suitable for carrying the invention into effect is diagrammatically illustrated, partly in section.

Referring more particularly to the drawing, the numeral 5 designates a pipe receiving pressure tar or residuum or hot conversion products from a system in which pressure conversion or distillation takes place. The temperature of the conversion products thus received will usually approximate the temperature of that part of the conversion system from which it is derived; that is, it will be at least approximately the minimum conversion temperature. Thus the temperature of the conversion products received by the pipe 5 may be 600 to 750° F. or higher. The pressure upon the conversion products within the pipe 5 will be about the same or somewhat less than that prevailing in the pressure distillation or conversion system with which it is connected, in which the pressure may be 4 atmospheres upward.

The hot conversion products, such as pressure tar or residuum, entering the system through the pipe 5 pass through the pressure reducing and control valves 6, in which there is some reduction in pressure. The products pass with somewhat smoother flow through the pipe 7 and enter a chamber 8, preferably formed as a compartment in the upper portion of a tower 9. As a result of the reduction in pressure upon the conversion products after leaving the conversion system, a substantial portion thereof is vaporized, and the vaporized portions pass out through the pipe 10 for further treatment as hereinafter more fully set forth. The unvaporized portions collect in the lower part of the compartment 8, the maximum liquid level main-

tainable therein being determined by an overflow pipe 11. The partition 12 separating the compartment 8 from the lower portion of the tower 9 is preferably sloped, this slope of the partition preventing accumulations of tarry deposits and facilitating cleaning. In general, liquid does not discharge through the overflow pipe 11, but is caused to pass through a valved pipe 13 into the lower compartment 14 of the tower 9. Where the supply of conversion products to the compartment 8 is not constant, or is intermittent or in "slugs", the level of the liquid body of unvaporized oil in the base of the compartment 8 varies (up to the maximum determined by the overflow pipe), taking care of such fluctuation. An approximately uniform flow to compartment 14 may thus be maintained. The compartment 14 is suitably provided with a number of baffle plates 15, which are illustrated as of the doughnut and disk type, although other types of baffle plates may be employed, if desired. The pipe 13 discharges unvaporized liquid from the compartment 8 at a point above the baffle plates in the compartment 14, although, if desired, baffle plates may also be provided above the point of discharge of the pipe 13. A body of liquid collects in the lower portion of the compartment 14, and a coil 16 is provided therein to which steam or other suitable inert gas, such as flue gas, carbon dioxide, hydrocarbon gas or the like may be supplied through the pipe 17 if the tar is larger in amount or lighter in quality than is desired. The steam or other inert gas thus supplied may be superheated, if desired. Ordinarily it is not superheated, and merely aids in driving off lighter portions of the unvaporized liquid derived from the compartment 8. The steam and vapors carried by it ascend the compartment 14 in countercurrent to the descending liquid, thus effectively stripping the latter of its lighter constituents. The steam and vapors from the compartment 14 pass out through the pipe 18, which joins the pipe 10 carrying the vapors separated in the compartment 8.

The vapors derived from the compartments 8 and 14 and passing through the pipe 10 enter a separating device 19, in which they are given a rapid helical movement, for example, by the vanes 20, resulting in a substantial separation of entrained particles of unvaporized oil preferably without any substantial reduction in velocity of the flow of the vapors and preferably with an increase therein. The separated unvaporized oil passes out of the separator 19

through a slot 21 into a small chamber 22, from which it is withdrawn by trapped pipe 23 and returned to the upper portion of the compartment 14, where it descends the column in the same manner as does the unvaporized liquid supplied from the compartment 8.

The vapors passing out of the separator 19 flow through the conduit 24 into a dephlegmating tower 25, which may suitably be provided with fractionating plates, for example, of the bubble type, as indicated at 26. A suitable cooling medium may be introduced directly or indirectly into tower 25; for example, oil of the character of the condensate from the vapors passing from the tower may be pumped in through pipe 26^a in any desired proportion. If desired, additional cooling may be supplied within the tower by any desired means. For example, a cooling medium, preferably a hydro-carbon oil having the characteristics of the oil collected as condensate in the base of the tower 25 may be pumped into the lower portion of the tower through pipe 27. The supply of such oil may be controlled by a pressure operated valve 27^a, which is in turn controlled (e. g. through control line 32) by the pressure or temperature in compartment 8, so that any substantial increase in pressure and consequent increase in flow of vapors to tower 25 or an increase in temperature in compartment 8 will increase the flow of cooling liquid through the pipe 27, to thereby so regulate the conditions within the tower 25 that the fractionated overhead product of the tower is of substantially uniform character, regardless of variations in the operating conditions within compartment 8 occasioned by the irregular flow of liquid residuum thereto from the line 7. Condensate formed within the tower 25 is drawn off through the valve controlled discharge pipe 28. Vapors pass out of the upper portion of the tower 25 through the line 29 into a condenser 30, from which the condensed liquids pass out through the line 31.

Those parts of the apparatus described up to the dephlegmating tower 25 are preferably well lagged with any suitable thermal insulation.

In a specific operation, pressure tar or residuum derived from the pressure distillation of an oil of the character of naphtha bottoms was received in the pipe 5 at a temperature of about 750° F. and a pressure of about 400 pounds. On reduction of pressure to about 10 pounds, a substantial temperature reduction took place, the temperature in the pipe 7 being approximately 650° F. From 5 to 25% remains unvaporized and separates in the chamber 8, the vaporized portion passing out through the line 10. A body of unvaporized oil is maintained in the base of compartment 8, its uppermost level being controlled by overflow 11. This body of oil serves as a reservoir from which a fairly smooth or constant supply of oil may be provided into compartment 14. The unvaporized portion passes into the tower chamber 14 and about 5 to 10% additional (based upon the original residuum supplied) may be removed in the compartment 14 by the stripping action of the steam supplied therein. A pressure tar residuum amounting to 5 to 20% is collected in the compartment 14 and oil is drawn off therefrom through the discharge line 14^a. Its temperature may be from 600 to 615° F. It may suitably be passed through a cooler or heat exchanger (not shown) after leaving the lower portion of

the compartment 14. It is of the character of an asphalt or fluxing or road oil, and may be used as such, according to its characteristics.

The combined vapors pass through the separator 19, any entrained oil carried thereby being returned to the compartment 14 through the line 23. The temperature of the combined vapors is, in the specific instance here noted, from 610 to 625° F. These vapors pass through the fractionating or dephlegmating tower 25, at the outlet of which a temperature of 350 to 400° F. is maintained. A distillate fraction is condensed in this tower, and drawn off through the line 28, this condensate having a gravity of about 23° to 25° A. P. I. This fraction is suitable for use as a cracking stock in pressure stills of other conversion devices, either alone or in conjunction with other stocks, as desired. The distillate fraction passing out of the dephlegmating tower through the vapor line 29 is condensed in the condenser 30, and may be rerun in any desired manner for the removal of its gasoline content. In the specific example herein set forth, the proportion of the conversion products collected as a residuum from the tower 14 amount to about 14%; those collected as an intermediate distillate from the dephlegmating tower 25 amount to about 70 to 76% and those collected as a light distillate, consisting largely of gasoline fractions, amount to about 10 to 15% of the original liquid conversion products delivered to the line 5.

Although a particular set of conditions have been specifically set forth herein, it is of course apparent that these should not be regarded as limitations upon the scope of the invention, as they merely illustrate a suitable set of operating conditions. They may be varied in accordance with the nature of the products which it is desired to collect; for instance, if a lighter fuel oil is desired, the temperature conditions prevailing in line 5 and in the separating compartment 8 and the stripping compartment 14 of the tower 9 may be correspondingly controlled; or if a greater proportion of intermediate distillate product is desired, the corresponding temperature conditions may be maintained in the tower 25.

We claim:

1. The method of distilling hot products derived from a pressure conversion system by contained heat which comprises discharging such products into a chamber in which a pressure below that of the conversion system is maintained, thereby vaporizing substantial portions of such conversion products, removing the vaporized portions thereof, maintaining a reservoir of unvaporized liquid in said chamber, discharging from a point below the level of said liquid separated unvaporized liquid at a regulated rate of flow into a second chamber, contacting it with an inert gaseous material in said second chamber, thereby removing lighter constituents therefrom, and separately conducting excess liquid from above the normal liquid level in the first mentioned chamber into the second chamber.

2. The method of distilling hot products derived from a pressure conversion system by contained heat which comprises discharging such products into a chamber in which a pressure below that of the conversion system is maintained, thereby vaporizing substantial portions of such conversion products, removing the vaporized portions thereof, maintaining a reservoir of unvaporized liquid in said chamber, dis-

- charging unvaporized liquid from said reservoir at a regulated rate of flow into a second chamber, contacting it with an inert gaseous material in said second chamber, thereby removing 5 as vapors lighter constituents therefrom, and mixing the vapors thus removed with the vaporized portions removed from the first chamber.
3. In apparatus for the distillation of hot hydrocarbon oils by contained heat, a tower, 10 a partition providing a compartment in the upper portion of said tower, a conduit for hot oil leading into said compartment, means for retaining a body of unvaporized oil therein, baffle plates in said tower below said partition, means 15 for supplying an inert gaseous medium below said baffle plates, means for supplying unvaporized oil from the upper compartment in said tower to a point in said tower below the partition, and means for sealing the upper compartment against ingress of vapors from below 20 said partition.
4. In apparatus for the distillation of pressure conversion products by contained heat, a chamber at reduced pressure, means for supplying hot conversion products thereto whereby vaporization takes place therein, means for maintaining a body of liquid oil therein, means for withdrawing vaporized oil therefrom, a second chamber provided in its upper portion 25 with a plurality of baffle plates, means for supplying an inert gas in said second chamber below said baffle plates, means for supplying liquid oil from the first chamber to the second chamber in regulated quantities and above the 30 baffle plates therein, a conduit leading from the second chamber and adapted to carry vapors therefrom, said conduit discharging said vapors into the means for withdrawing vapors from the first mentioned chamber.
- 40 5. In apparatus for effecting distillation of pressure converted products by contained heat, a chamber at reduced pressure, means for supplying hot conversion products thereto, whereby vaporization is effected by reduction in pressure therein, a vapor conduit for removing vaporized products from the said chamber, means for maintaining a body of liquid oil in said chamber, a second chamber provided with distilling plates, means for supplying an inert gaseous medium below said distilling plates, means 45 for supplying unvaporized liquid from the first chamber to the second chamber above said distilling plates, a vapor conduit leading from the upper portion of the second chamber and joining the vapor conduit leading from the first chamber, means for separating entrained liquid from the vapors issuing from the two chambers, and means for returning separated liquid to the second chamber.
- 55 6. In apparatus for effecting distillation of pressure converted products by contained heat, a tower, a sloping partition therein separating said tower into an upper compartment and a lower compartment, an overflow pipe passing 60 through said partition and extending from the upper compartment into the lower compartment said overflow pipe determining the level of unvaporized liquid to the second compartment, and 65 partition, a plurality of distilling plates in the lower compartment, means for supplying an inert gaseous medium into the lower portion thereof, a valved conduit leading from the lower portion of the upper compartment into the lower compartment above the distilling plates therein and adapted to supply a controlled flow of unvaporized liquid to the second compartment, and 70 means for withdrawing vapor from each of said compartments.
7. The method of distilling hot products derived from a pressure conversion system by contained heat, which comprises discharging such products in an irregular stream into a chamber in which a pressure below that of the conversion system is maintained, thereby vaporizing substantial portions of such conversion products, 80 removing the vaporized portions thereof, maintaining a reservoir of unvaporized liquid in said chamber, discharging unvaporized liquid from said reservoir at a regulated rate of flow into a second chamber, causing it to flow downwardly therethrough in thin layers in countercurrent to ascending steam, thereby removing as vapors lighter constituents therefrom, mixing the vapors thus removed with the vaporized portions removed from the first chamber, extracting entrainment from said vapors, and returning it to 85 the second chamber.
8. In apparatus for distilling pressure converted products by their contained heat, a reduced pressure chamber, means for supplying the hot conversion products thereto, means for withdrawing vaporized portions of the conversion products therefrom, means for maintaining a body of liquid in said chamber, a second chamber, means for supplying an inert gas in said 90 second chamber, means for causing a regulated flow of liquid from the liquid body in the first chamber into the second chamber, and a liquid sealed overflow for conveying excess liquid from the first chamber into the second chamber.
9. In apparatus for the distillation of pressure conversion products by their contained heat, a chamber at reduced pressure, means for supplying hot conversion products thereto, whereby vaporization takes place therein, means for separately removing vaporized products therefrom, means for maintaining a liquid body therein, a stripping column having a chamber therein for retaining a liquid body, means for supplying an inert gas in said liquid body, a conduit connecting the first chamber with the upper portion of 100 said column and adapted to permit the flow of unvaporized oil from the first chamber, means for regulating the flow of oil through said conduit, and a liquid sealed overflow for conveying excess liquid from the first chamber into the second chamber.
10. In apparatus for the distillation of pressure converted products by contained heat, said products being derived from the conversion of hydrocarbon oils by heat under pressure for the formation of gasoline, an unheated separating chamber, means for conducting such residuum from a converting means to the separating 115 chamber, and for reducing pressure thereon before entering the latter, a fractionating column, means for discharging vapors from the separating chamber into the fractionating column, means for introducing an oil containing gasoline 120 constituents into the upper part of said column to effect cooling therein, means operated by pressure conditions in the separating chamber for introducing additional cooling oil into a lower point in the column, and means for withdrawing vapors containing gasoline constituents 125 from said column.
11. The method of distilling hot products derived from a pressure conversion system by contained heat, which comprises discharging such 130 products in an irregular stream into a chamber

- in which a pressure below that of the conversion system is maintained, thereby vaporizing substantial portions of such conversion products, removing the vaporized portions thereof, maintaining a body of unvaporized liquid in said chamber, withdrawing liquid from said body of unvaporized liquid at a substantially uniform rate of flow and discharging such withdrawn liquid into a second chamber, contacting it with inert gaseous material in said second chamber, thereby removing lighter constituents therefrom, and separately conducting excess liquid from said body of unvaporized liquid and above its normal liquid level into said second chamber. 5
12. The method of distilling hot products derived from a pressure conversion system by contained heat, which comprises discharging such products in an irregular stream into a chamber in which a pressure below that of the conversion system is maintained, thereby vaporizing substantial portions of such conversion products, removing the vaporized portions thereof, maintaining a reservoir of unvaporized liquid in said chamber, discharging unvaporized liquid 10 from a point below the level of said reservoir at a regulated rate of flow into a second chamber, causing it to flow downwardly therethrough in countercurrent to ascending steam and thereby removing lighter constituents of said liquid, and separately conducting excess liquid from above the normal liquid level of said reservoir of unvaporized liquid into said second chamber. 15
13. In apparatus for the distillation of hot hydrocarbon oils by contained heat, a tower, a partition providing a compartment in the upper portion of said tower, a conduit for hot oil leading into said compartment, means for retaining a body of unvaporized oil therein, baffle plates in said tower below said partition, means for supplying an inert gaseous medium below said baffle plates, means for supplying a regulatable flow of unvaporized oil from the upper compartment in said tower to a point in the tower below the partition, and a separate, vapor-sealed overflow pipe extending through said partition for determining the maximum liquid level in the compartment in the upper portion thereof. 20
14. In apparatus for the distillation of pressure converted products by contained heat, said products being derived from the conversion of hydrocarbon oils by heat under pressure for the formation of gasoline, an unheated separating chamber, means for conducting such residuum from a converting means to the separating chamber and for reducing pressure thereon before entering the latter, a fractionating column, means for discharging vapors from the separating chamber into the fractionating column, means for introducing cooling oil containing gasoline constituents into the upper part of said column, means for introducing additional cooling oil into a lower point in the column, and means operated by conditions in the vapor space in the separating chamber for controlling the supply of said second cooling medium. 25
15. In an apparatus for effecting distillation of pressure converted products by contained heat, an unheated separating chamber, means for introducing hot pressure converted products into said chamber, means for reducing the pressure on said products before entering said chamber, a fractionating device, means for conveying separated vapors from said chamber to said fractionating device, a stripping column, means 30 for supplying liquid from said unheated chamber to said stripping column, means for supplying stripped vapors from said stripping column to said fractionating device, means for supplying a cooling medium in said fractionating device, and means operated by conditions in the vapor space in the separating chamber for controlling the supply of said cooling medium. 80
16. In apparatus for effecting distillation of pressure converted products by contained heat, an unheated separating chamber, means for introducing hot pressure converted products into said chamber, means for reducing the pressure on said products before entering said chamber, a fractionating device, means for conveying separated vapors from said chamber to said fractionating device, a stripping column, means for supplying liquid from said unheated chamber to said stripping column, means for supplying stripped vapors from said stripping column to said fractionating device, means for supplying a cooling medium in said fractionating device, and means operated by pressure conditions in the vapor space in the separating chamber and the stripping column for controlling the supply 85 of said cooling medium. 90
17. In the art of converting higher boiling hydrocarbons into lower boiling ones wherein the oil is subjected to regulated conditions of pressure and temperature in a conversion zone to produce a residuum and a lighter fraction, the improvement which comprises discharging the heated residuum in irregular quantities into a chamber in which a pressure below that of the conversion system is maintained, thereby vaporizing a portion of said residuum, maintaining a reservoir of unvaporized residuum in said chamber, discharging unvaporized residuum from said reservoir at a regulated rate of flow into a second chamber wherein it is contacted with an inert gaseous material and a portion of said liquid is vaporized and withdrawing the vapors from each of said chambers and passing them to a common fractionating means. 95 100
18. The method of flash distilling hot products derived from a pressure conversion system that comprises discharging such products in irregular quantities into a chamber in which a pressure materially below that of the conversion system is maintained, thereby vaporizing substantial portions of such conversion products, maintaining a reservoir of unvaporized liquid in said chamber, normally withdrawing unvaporized liquid from a point below the level of the liquid and passing it to a second chamber and distilling the said liquid therein, separately withdrawing additional liquid from the first chamber only when the liquid level of the reservoir of liquid therein exceeds a predetermined point and passing the liquid so withdrawn to said second chamber for distillation therein. 110 115
19. The method of distilling hot products derived from a pressure conversion system by contained heat, which comprises discharging such conversion products in irregular quantities into a chamber in which a pressure substantially below that of the conversion system is maintained, thereby vaporizing a portion of such conversion products and producing vapors in said chamber in varying amounts, separately discharging the liquid portion of said products from said chamber in a regular flow into a second chamber wherein it is distilled and a portion of said liquid is vaporized, separately with- 120 125 130 135 140 145 150

drawing the vapors from each of said chambers and passing them to a common fractionating means, and controlling the conditions of operation in said fractionating means to compensate for the irregular supply of vapors thereto from said first-named vaporizing chamber, thereby securing a fractionated product of substantially uniform characteristics.

20. The method of distilling hot products derived from a pressure conversion system by contained heat, which comprises discharging such conversion products in irregular quantities into a chamber in which a pressure substantially below that of the conversion system is maintained, thereby vaporizing a portion of such conversion products and producing vapors in said chamber in varying amounts, separately discharging

the liquid portion of such products from said chamber in a regular flow into a second chamber wherein light constituents are stripped from said liquid by an inert gas, separately withdrawing the vapors from each of said chambers and passing them to a common fractionating means, and controlling the conditions of operation in said fractionating means to compensate for the irregular supply of vapors thereto from said first-named vaporizing chamber, thereby securing a fractionated product of substantially uniform characteristics.
